REMEDIAL FOOT SUPPORT

Albert Woodthorpe, Toronto, Ontario, Canada

Application February 1, 1951, Serial No. 208,861

5 Claims. (Cl. 36—71)

1

This invention relates to improvements in remedial foot supports, and more particularly to supports of the type disclosed in United States Patent No. 1,928,634 which was issued to Sterling Le Roy Spicer and Harold Stewart Bovaird on October 3, 1933.

In supports for the relief of arch troubles and kindred ailments it is common to provide pads or artificial elevations which exert direct pressure upward and into the foot tissues. These pads or elevations tend to become rigid as the body weight bears down upon them, and unyielding pressures are created which do not encourage normal re-alignment of the muscles and ligaments of the foot.

According to this invention, these disadvantages may be overcome by providing an essentially flat and smooth surface for the foot to rest upon. This surface is constructed of resilient material, and is supported by a resilient mechanism in such a way that the surface readily accommodates itself to the actual needs of the individual foot, providing free and natural muscular, ligamentary and osseous action, and specifically avoiding all direct pressure by localized parts. Since the requirements of different feet vary, this invention permits the body weight to determine how much support is needed, rather than giving arbitrary support in definite areas only. Foot balance is improved, normal circulation of the blood is encouraged, the ligaments of the feet are properly re-adjusted, permanent correction and strengthening of the foot tissues is encouraged, and more enduring comfort and improved posture in walking and standing is achieved. Relief is afforded to the feet, legs, hips and spine.

In this invention, resilient support is provided in special places which are not supported in any of the conventional arch supports. In its action the support also massages the foot during locomotion.

It is the object of this invention to achieve the aforementioned results in a remedial foot support which is of simple construction, easily produced, fitted and adjusted, of light weight and well insulated and ventilated.

Other objects and advantages of the invention will be apparent from the following description.

In the drawings which illustrate one embodiment of the invention, and in which like reference numbers indicate corresponding parts in the several views:

Fig. 1 is a perspective view of the bottom of a remedial foot support for the left foot;

Fig. 2 is a bottom plan view of the support;

Fig. 3 is a side view showing the support placed in the shoe and supporting a foot. Part of the shoe is cut away to show the arch support;

Fig. 4 is a sectional view taken along line 4—4 in Fig. 2; and

2

Fig. 5 is a sectional view taken along line 5—5 in Fig. 2.

Fig. 3 shows a left foot 1 fitting into a shoe which has the usual upper 2 and sole 3. The foot rests upon an arch support constructed in accordance with this invention.

In the arch support illustrated, a mainplate 7, made of a resilient metal such as finely spun Swedish steel, is preferably formed with substantially parallel edges, the rear end being rounded and the front end suitably truncated. The mainplate is slightly arched from end to end. As shown in Fig. 3, the arch support is so positioned in the shoe that the front end of the mainplate lies just to the rear of the ball of the foot.

Attached above mainplate 7 by rivets 5 is a special non-absorptive pad 6 made of compressed cork compound or similar soft resilient material. Pad 6 is the same shape as mainplate 7, except that the pad is somewhat wider adjacent the instep of the foot.

Secured above pad 6 by rivets 5 is a foot piece 4 which is cut so that its contour conforms generally with that of the inside of the shoe. Foot piece 4 has a forward flap which projects under the ball of the foot, beyond pad 6 and mainplate 7, the flap being skived thin in order to avoid impression upon the foot. The rear edge 30 of foot piece 4 is trimmed to fit against the heel portion of the shoe.

A longitudinal metallic tongue 9 lies below the mainplate 7. The rear end of the tongue is secured to the heel end of the mainplate by rivets 8. The tongue is narrower than the mainplate, but has a T-head 9^a and transverse bars 9^b and 9^c which projects not beyond the edges of the mainplate. In the preferred embodiment illustrated, T-head 9^a lies just behind the transverse arch of the foot, bar 9^b extends below the instep, and bar 9^c projects outwardly near the heel.

As shown in Fig. 5, the front and rear ends of tongue 9 are flat, but the tongue is slightly arched between its ends. The tongue serves as a resilient clamping member which firmly holds resilient pads 10, 11 and 12 between the tongue and the mainplate. Normally, the resilient pads will be clamped above T-head 9^a and bars 9^b and 9^c respectively, but they may be shifted in position to meet the requirements of the individual foot. Pad 12, over bar 9^c near the heel, provides resiliency at a place which has been neglected in other foot corrective devices, and furnishes additional comfort and corrective action and improves the balance of the wearer.

Making T-head 9^a flat, as shown in Fig. 5, causes the tongue to bend toward the mainplate at its front end to hold pad 10 securely in position. The edges of T-head 9^a are curved up-

wardly in a lip which further prevents pad 10 from slipping forward, and also prevents damage to the sole of the shoe on which the tongue bears.

Tongue 9 has been made narrow and flexible, and has a slight upward curvature, so that downward pressure on the tongue at one point will not diminish its resilient action at other points. The other elements of the tongue are affected only slightly and operate almost independently to provide resilient action over the whole of the support. Being light and resilient, the tongue is free to twist and to bend transversely as well as longitudinally and thus to respond to the constant shifting of weight from point to point which occurs during walking.

It is to be understood that the tongue 9 may be E- or F-shaped with a longitudinal stem providing a resilient base along the longitudinal arch of the foot, and bars extending out from the stem across the bottom of the foot. Any of these constructions encourage normal weight distribution upon the metatarsal heads and the heel, rather than lifting or supporting directly any sagging tissue, and thus avoid any crutch-like action which prevents the normal re-alignment of muscles and ligaments. Because of the resilient action which encourages nature, the wearing of this support is not habit-forming. The support is not weakening, but rather strengthens the foot tissues by encouraging their free action in a correct manner.

It is thought that it will be clear from the above description that the one-piece, longitudinal tongue 9, is an improvement over the longitudinal and transverse spring strips in Patent No. 1,928,634. The present construction eliminates the awkward transverse spring strip, which was open at one side only, and, being riveted to one edge of the mainplate, tended to weaken the mainplate and to decrease its resiliency. The special rivets of the transverse spring strip interfered with the smooth surface of the mainplate, and these have likewise been eliminated. The improved support has greater versatility since the resilient pads 10, 11 and 12 can be positioned and adjusted to meet individual needs.

The improved design of tongue 9 and the use of the resilient pad 11 below the instep have done away with the need for a metallic lip on plate 7 to support pad 6 beneath the waist of the foot. Similarly, the metatarsal pad, attached to the mainplate in Patent No. 1,928,634, can be eliminated. Any rigid or irritating points above the mainplate are thus avoided.

The felt pad in Patent No. 1,928,634 has been replaced by a special pad 6 of compressed cork and paper, or the like which is non-absorptive, of reduced bulk, serves as an excellent heat insulator, and, through improved ventilation, relieves greatly fetid conditions of the feet.

In order that only one size of arch support need be constructed, the rear edge of the foot piece 4 is not trimmed until the support has been correctly fitted at its front end to the foot of the individual wearer. The rear edge is then cut to conform with the heel portion of the shoe, so that the individual foot is supported in exactly the right position. With the foot so positioned, the arch support does not move in the shoe. Body weight near the front of the support prevents longitudinal forward movements and the heel portion of the shoe prevents movement rearwardly. Because of this, the rearward projection of the longitudinal metallic strip in Patent No. 1,928,634 can be eliminated.

It is thought that the construction and the use of the invention will be apparent from the above description of the various parts and their purpose. It should be understood that the form of the invention herewith shown and described is to be taken as a preferred example of the same and that various changes in the shape, size and arrangements of parts may be resorted to without departing from the invention as defined in the subjoined claims.

What I claim as my invention is:

1. In a remedial foot support, a mainplate, a resilient tongue of less width than the mainplate, secured at one end to the heel end of the mainplate, and extending longitudinally below the mainplate and normally closely approximating the adjacent surface of the mainplate throughout its length to clamp a resilient pad or pads against the mainplate, but adapted to be pulled away from the mainplate for the insertion of such pad or pads, and a transverse bar extending from the said tongue.

2. In a remedial foot support, a mainplate, a resilient tongue of less width than the mainplate, secured at one end to the heel end of the mainplate, and extending longitudinally below the mainplate and normally closely approximating the adjacent surface of the mainplate throughout its length to clamp a resilient pad or pads against the mainplate, but adapted to be pulled away from the mainplate for the insertion of such pad or pads, and a transverse bar extending from the said tongue near the heel end of the said tongue.

3. In a remedial foot support, a mainplate, a resilient tongue of less width than the mainplate, secured at one end to the heel end of the mainplate, and having a T-head at the other end, said tongue extending longitudinally below the mainplate and normally closely approximating the adjacent surface of the mainplate throughout its length to clamp a resilient pad or pads against the mainplate, but adapted to be pulled away from the mainplate for the insertion of such pad or pads, and a transverse bar projecting intermediate the ends of the said tongue.

4. In a remedial foot support, a mainplate, a resilient tongue of less width than the mainplate, secured at one end to the heel end of the mainplate, and having a T-head at the other end, said tongue extending longitudinally below the mainplate and normally closely approximating the adjacent surface of the mainplate throughout its length to clamp a resilient pad or pads against the mainplate, but adapted to be pulled away from the mainplate for the insertion of such pad or pads, and a plurality of bars extending from the said tongue.

5. In a remedial foot support, a mainplate, a resilient tongue of less width than the mainplate, secured at one end to the heel end of the mainplate, and having a T-head at the other end, said tongue extending longitudinally below the mainplate and normally closely approximating the adjacent surface of the mainplate throughout its length to clamp a resilient pad or pads against the mainplate, but adapted to be pulled away from the mainplate for the insertion of such pad or pads, a transverse bar projecting from one side of the tongue near the end at which the tongue is secured to the mainplate, and a transverse bar projecting from the other side of the tongue and intermediate the ends of the tongue.

ALBERT WOODTHORPE.
